COMBINATION VENTILATOR AND CABINETS

Donald E. Dailey, Center Township, Vanderburgh County, Ind., assignor to American Air Filter Company, Inc., Louisville, Ky., a corporation of Delaware

Filed May 2, 1960, Ser. No. 60,408

Term of patent 14 years

(Cl. D62—4)

FIGURE 1 is a perspective view of a combination ventilator and cabinets showing my new design.

FIGURE 2 is an enlarged fragmentary view of the panelling material on the end of the cabinet and on the lower front of the ventilator.

FIGURE 3 is an enlarged cross sectional view of the panelling material taken on the line 3—3 of FIGURE 1.

The rear of the ventilator and cabinets is substantially plain.

The right end of the right cabinet in FIGURE 1 is substantially the same in appearance as the left end of the left cabinet shown in FIGURE 1. The grille panelling material on these ends of the cabinets is the same as that on the lower front of the ventilator.

The grille panelling pattern is shown only in part on the end of the cabinet and the lower front area of the

ventilator. It is to be understood that the pattern covers the entire grille area.

The dominant features of my design reside in the full line portions.

I claim:

The ornamental design for a combination ventilator and cabinets, as shown and described.
